APPARATUS FOR OPENING COMPRESSED
PACKAGES

John R. Nordstrom, Portland, Oreg.

Application August 14, 1947, Serial No. 768,680

11 Claims. (Cl. 100—12)

1

It is well known that many products ready for the retail markets or as the raw materials of products in manufacture which have inherent resiliency are exceedingly bulky for handling, storage or transportation. To eliminate these disadvantages inherent in such products, their normal density and dimensions are sometimes reduced by compression after manufacture and when made ready for warehousing and shipment, whenever such material can be readily re-expanded by the ultimate user. Coil and other types of springs are usually handled and packaged in this manner. It is now the standard practice to package the springs used in the manufacture of mattresses and bedded furniture, in a highly compressed and, therefore, compact package. While this method of packaging for handling, storing, and transporting is satisfactory to the fabricator, shipper, and ultimate user, it does, however, create a serious problem to the ultimate user occasioned by the necessity of re-expanding these goods to their normal density and dimensions.

In the case of coil springs used in manufacturing mattresses and bedded furniture, the problem is extremely serious since a large quantity of coil springs can be highly compressed into a relatively small package without fear of damage or loss to their normal resiliency when the compressed package is opened and the springs are allowed to resume their normal state. It is a proven fact that in opening such highly compressed packages, workmen have been injured in spite of caution employed in handling them; and because of this dangerous condition created by the opening of these compressed packages, much time is consumed in opening such packages. My invention eliminates the hazards referred to and saves considerable time in opening compressed packages.

The main object of my invention is to provide apparatus for opening compressed packages expeditiously and safely.

Another object of the invention is to provide apparatus for opening compressed packages which is simple in construction and application and which can be moved about with little effort.

Still another object of the invention is to provide apparatus for opening compressed packages which is safe to handle, easy to assemble, or disassemble and which is readily adaptable to fit various types and sizes of compressed packages.

The accompanying drawings forming a part of this specification, illustrate the structural features of the invention, and in order to describe the invention in detail, reference is made to said drawings, wherein:

2

Fig. 1 is a perspective of apparatus embodying the invention and showing the position of a package when under compression and after the compression has been removed therefrom;

5 Fig. 2 is a perspective, side view, of a segment of one of the package supports showing the structural characteristics of the slideable anchor and the slideable pulley embodying features of my invention;

10 Fig. 3 is a side view, partially in section, and partially broken away, of the drum and brake structure revealing features of my invention;

Fig. 4 is a perspective segment of one of the supports showing the method employed in securing it to the end support;

15 Fig. 5 is a sectional view, taken on line 5—5 of Fig. 1, showing the structural features of one of the restraining bars and the position of the pulley in relation thereto;

20 Fig. 6 is an end elevational view showing one of the end pulleys and control arrangement therefor;

Fig. 7 is a sectional elevation, taken on line 25 7—7 of Fig. 6, to reveal the structural characteristics of the pulley controls;

Fig. 8 is an end view of one of the pulleys used to change the direction of travel of the rope and reveals the loose manner in which it is secured in order to allow sufficient play when the rope changes its position on the drum; and

30 Fig. 9 is a bird's-eye view of a modified arrangement for correlating the rotation of the end pulleys to provide equal tension on the ropes.

The complete apparatus embodying the principles of my invention is shown in Fig. 1 wherein a fanciful package 1 is shown in full line in a compressed state ready to be expanded by the employment of the apparatus and in dotted line, identified by numeral 1' in an expanded state after the pressure in the package has been released by the apparatus. Package 1 is positioned upon a pair of supports 2 and 3 lying in the same plane and spaced in parallel relation to each other. These supports are removably secured to the end support 4. Supports 2 and 3 are shown as T-shaped although they may be I-shaped. The end support 4 may be made from angle iron or may be T-shaped or I-shaped, if desired.

35 Fig. 4 discloses the method employed in securing supports 2 and 3 to end support 4. This is accomplished by welding or securing by any standard method L-shaped brackets 5 and 6 to the vertical wall of end support 4 so that a space 7 is provided between the top of the brackets and the underside of the end support 4 approximately equal to the thickness of the top portion of the supports 2 and 3. The brackets 5 and 6 are also

spaced apart to provide a pocket 8 wide enough to receive the leg of each of the supports 2 and 3. Coinciding openings 9 and 10 are provided in the supports 2 and 3 and brackets 5 and 6 to receive the standard bolt and nut assembly 11 as shown in Fig. 7. By this arrangement, the supports 2 and 3 are fixedly and rigidly secured to the end support 4 and yet are readily disengageable for shipment or storage. A pair of casters 12 of standard construction are secured to the ends of supports 2 and 3 in any desirable manner.

Referring again to Fig. 1, a drum and brake assembly support 13 is welded or otherwise centrally secured to the wall of end support 4 and extends therefrom in the same plane as the top of the end support. A pair of casters 14 are secured to support 13 in any desirable manner. The casters secured to the supports 2, 3, and 13, give mobility to the apparatus. Pairs of legs 15, and 16, are fixedly secured to support 13 in vertical spaced parallel relationship to each other and provide the basic support for the drum and brake assembly hereafter to be described. Pairs of reinforcing rods 17 and 18, secured at right angles to legs 15 and 16, are positioned in spaced parallel relationship to each other at and near the top of said legs.

A pair of bracket plates 19 and 20 are secured to pairs of legs 15 and 16 respectively adjacent their ends and each plate has coinciding openings therethrough to support bearings 21 and 22. A drum 23, having end walls 24 and 25 and a divider wall 26, has its shaft 27 journaled in bearings 21 and 22 respectively. Appropriate openings, not shown, are provided in the divider wall 26 into which the ends of the ropes 28 and 29 may be anchored in any desired manner. A thrust washer 30 is provided between the end wall 24 and the wall of thrust bearing 21.

A cylindrical pressure plate 31 is slidably positioned on shaft 27 and a floating brake disc 32, made of fibrous material or such other appropriate material as fits the requirements, is positioned between end wall 25 and pressure plate 31 and is held intimately under pressure between them by a plurality of coil springs 33. These springs are compressed between pressure plate 31 and bracket plate 20 and are kept in lateral alignment by a plurality of externally threaded pins 34 extending from pressure plate 31 and slidably extending through bracket plate 20 and each of said pins has a lock nut 35 threaded thereon.

A brake release collar 36 fits over and is slidably keyed to the outer surface of bearing 22. One of its faces 37 is angled to coincide with a like face 38 provided on swash plate 39. Swash plate 39 is also positioned over the outer surface of bearing 22 but in rotatable relation thereto. A brake release handle 40 extends from swash plate 39. A retaining collar 41 is movably secured to the outer surface of bearing 22 and holds faces 37 and 38 in intimate contact at all times. A plurality of brake release fingers 42 have one of their ends positioned in grooves 43 provided on the periphery of collar 36 adjacent to its vertical face and the other of their ends are provided with an opening 44 which fits over pin 34. Adjusting set screws 45 are threaded disposed in fingers 42 and engage the outer surface of the bracket plate 20. From the foregoing description, it is apparent that by moving handle 40 about the outer surface of bearing 22, collar 36 is moved toward or away from bracket plate 20 and through the action of fingers 42, tension on springs 33 is increased or decreased in direct proportion to the

degree of rotation of handle 40. Thus this swash plate movement increases or decreases the braking action between the end wall 25 and pressure plate 31 on the floating brake disc 32. A crank 46 is removably secured to shaft 27 and is employed to wind and unwind the ropes 28 and 29 when necessary.

A pair of restraining bars 47 and 48 are placed on top of the representative package 1 in spaced relation to each other and to supports 2 and 3, when it is desired to open said package. Each of said bars has the same structural characteristics, therefore, a detailed description of one will suffice for both. Restraining bar 48 is made of two sections 49 and 50 of different lengths and which are hinged together, as at 51, in order to accommodate the restraining bars to the top contours of the package being opened. Both of the sections of restraining bar 48 possess the same structural design shown in Fig. 5, and, as will be seen, is fabricated to the same shape as standard overhead track beams, and provides a pair of slide tracks 52 and 53 within the interior of the restraining bars on which pulley mount 54 is fixedly positioned in the track formed in section 49 and has a pulley (not shown) rotatably secured therein, and the pulley mount is removably secured in relation to the restraining bars in any desirable manner as by a nut and bolt arrangement 55. A guide pin 56 extends downwardly from the opposite end of pulley mount 54, and this pin normally contacts the side of the package to be opened. Another pulley 51 is rotatably secured in the usual manner to the opposite end of section 49 of the restraining bars. Slidably positioned in relation to section 50 of the restraining bars is another pulley mount 53 having the same features as pulley mount 54 such as a pulley 59 mounted in the usual manner and a pin 60 depending therefrom.

From the foregoing, it will be observed that each of the restraining bars 47 and 48 is divided into two sections, and each have a pair of pulley mounts, one of which is in fixed position to section 49 and the other of which is in slidable relation to section 50.

Ropes 28 and 29 pass over the various pulleys positioned within the restraining bars and have their free ends, only one of which is revealed, as shown at 61, anchored in any desirable manner, as by a single Blackwall Hitch formed in the pairs of eyes 62 which are provided on the anchor 63, slidably positioned in relation to support 2. A like anchor, not shown, is provided for the other rope 28, and it is positioned in slidable relation to support 3. In addition to the eyes 62, each anchor 63 has a pair of grooves 64 formed in its underside in which the sides 65 and 66 of supports 2 and 3 fit. By this arrangement, the anchor 63 may be adjusted on the supports 2 and 3 to accommodate packages of different widths.

At the junctures of supports 2 and 3 with end support 4, a pair of identical bracket assemblies 67 and 68 extend upwardly from support 4, and each of these bracket assemblies are disclosed in detail in Figs. 6 and 7. Since these assemblies are identical in construction only one will be described in detail. Bracket assembly 68, consists of pairs of legs 69 and pairs of legs 70, all positioned in vertical spaced parallel relation to each other. Pairs of rope friction prevention rollers 71 and 72 are rotatably secured to the legs at and adjacent to the top of pairs of legs 69 and 70 and, between them, provide a passage for the ropes 28 and 29 which insures

against their damage from friction and premature wear as they pass therethrough. In addition, the supports for these rollers provide greater rigidity to the pairs of legs.

A pair of bearing supports 73 are secured to and between said pairs of legs and a shaft 74 is journaled therein so that a portion of said shaft extends beyond one of the bearing supports, as shown in Fig. 7. A pulley 75, having a groove to accommodate the ropes, is keyed to this shaft between the bearing supports and another grooved pulley 76 is secured to the extended portion of shaft 74.

A stub shaft support 77, having stub shaft 78 extending therefrom is pivotally supported by a bolt and nut combination as shown at 78a. A disc 79, made of soft rubber, and the periphery of which is flat and slightly wider than the periphery of pulley 75, is rotatably positioned on stub shaft 78. A pin 80 extends from support 77 and a spring 81 under tension is anchored thereto and to one of the pairs of legs 10 so that the peripheries of the pulley 75 and disc 79 are in intimate contact at all times. Secured to one side of the disc 79 in any standard manner is a friction plate 82 which is in contact with the wall of support 77 at all times. Coil spring 83, under compression by butterfly nut 84 is positioned around the stub shaft 78 and contacts the side of disc 79. It will be seen that by varying the tension on coil spring 83, the pressure between the friction plate 82 and the wall of support 77 is varied and the relative ease of movement of the pulley 75 is proportionately controlled.

An endless V-belt 85 connects pulleys 76 and is crossed so that one rotates clockwise while the other rotates counter clockwise. This arrangement permits the ropes to move simultaneously and under the same degree of tension or approximately so. A pair of angled brackets 86 are loosely secured to end support 4 as shown at 87, in Fig. 8 and each of them supports a V-shaped pulley 88 under which ropes 28 and 29 pass to change their angle of travel. By securing the brackets 86 loosely the ropes are permitted to change their angle, as shown in Fig. 8, in accordance with their positions assumed on the drum 23 when the same is rotated.

In Fig. 9, is shown a modified method for providing coordinated rotation between pulleys 75. This is accomplished by substituting beveled gears 89 for pulleys 76, and substituting shaft 90, having beveled gears 91 at each end thereof in mesh with gears 89, for V-belt 85.

Mode of operation

The foregoing completes the detailed description of the invention and the following outlines the manner of applying the invention for opening compressed packages. When a compressed package is to be opened, and its contents re-expanded to its normal density and dimensions, the package is placed upon supports 2 and 3 and restraining bars 47 and 48 are then placed on top of the package in direct alignment with supports 2 and 3 respectively with the downwardly extending guide pins 56 contacting the side of the package. Anchors 63 are then slidably positioned in relation to supports 2 and 3, so that the ropes 28 and 29, which are secured thereto, are approximately at right angles to supports 2 and 3 and in contact with the other side of the package. Restraining bars 47 and 48, each being hinged, accommodate themselves to the contour of the top of the package and pulley mounts 58, since they

are in slidable relation to these bars, accommodate themselves in relation thereto so that ropes 28 and 29 may assume the vertical position as heretofore stated.

Having thus arranged the restraining bars and anchors about the compressed package, the ropes are then wound on the drum 23, so that all the slack is removed and the restraining bars are held in taut relation to the top of the compressed package. By the use of friction discs 79, which are held in intimate contact at all times against pulley 75, and by providing adjustable means for controlling the speed of rotation of said discs, the ropes 28 and 29 are never allowed to move uncontrolled about the various pulleys over and under which they pass as they travel between the respective anchors provided on the drum 23 and by anchors 63. As an additional control for these ropes, and to insure identical tautness as they are simultaneously "payed-out," or their slack removed, pulley 76, connected by V-belt 85 are provided and move at the same speed and control as pulleys 75.

When the slack of the ropes has been removed, the ropes are held on the drum by the brake mechanism heretofore described in detail, the restraining bands, wire or other means employed to maintain the package in a compressed condition, are then removed, and such pressure as was restrained by these elements, are then assumed by the anchors 63, restraining bars 47 and 48, and ropes 28 and 29. The pressure is then slowly released by moving the swash plate 39 which permits brake release collar 36 to slide on the outer surface of bearing 22 and thereby release the normal tension on springs 33 which in turn proportionately releases the compression maintained between wall 25, pressure plate 31 and floating brake disc 32. The drum 23 is, therefore, allowed to slowly pay-out ropes 28 and 29, and the package is permitted to slowly expand under this restraint until its contents has assumed its normal density and dimensions.

Structural variations embodying the principles of my invention as disclosed in the foregoing description may suggest themselves to those skilled in the art; the invention, therefore, is not limited to the structural details herein shown and described as changes may be made therein without departing from the broad spirit of the invention.

Having thus disclosed my invention, I claim:

- Apparatus for controlling the opening of compressed packages, comprising supports for said packages, a pair of ropes, a drum for said ropes, a floating brake disc, a pressure plate positioned in intimate relation to said brake disc, resilient means associated with said pressure plate to maintain said plate in contact with said brake disc, means associated with the resilient means to vary the pressure of said pressure plate on said brake disc, means slidably positioned on said supports adapted for securing the ends of said ropes, and means associated with said ropes and confined thereon between said slidable means and said drum for aiding the movement of said ropes, said means associated with the ropes adapted to be positioned on top of said packages.

- Apparatus characterized as in claim 1 wherein the supports are T-shape in cross-section and the means slidably positioned on the supports consists of a pair of means, one for each support, each means being channel shaped and having a pair of grooves formed in the underside thereof of a depth and width adequate to permit each of said means to slidably engage the sides

of said support, and a pair of eyes extending upwardly from each of said means.

3. Apparatus characterized as in claim 1 wherein in the means associated with said ropes for aiding their movement consists of a pair of restraining bars each formed of two sections for partially adapting said bars to follow the top contours of a package, fixed means associated with one section of each of said bars over which said ropes pass, and slidable means associated with each of the other sections of said bars over which said ropes pass, both of said means being adapted to confine said package within the close embrace of said ropes.

4. Apparatus for re-expanding compressed packages, comprising a support for said packages, a pair of hollow restraining bars positionable on top of the packages, a pair of anchors slidably secured to said support, a drum, means for controlling the speed of rotation of said drum, a 15 pair of ropes secured to said drum and to said anchors, said ropes being threaded through said restraining bars, a pair of grooved pulleys secured to said support under which said ropes are positioned, means for controlling the movement of said pulleys, and means associated with said pulleys for uniformly controlling the movement of said ropes.

5. Apparatus as described in claim 4 wherein the restraining bars consist of two hinged sections adapted to partially follow the contours of the top of the package, and a pair of pulley mounts disposed in each of said restraining bars, one of said pulley mounts in each of said bars being disposed in fixed relation thereto and the other of said pulley mounts in each of said bars being positioned in slidable relation to its respective restraining bar.

6. Apparatus for controlling the opening of compressed packages, comprising supports for said packages, a pair of ropes, a drum for said ropes, rotatable means for simultaneously controlling the movement of said ropes, means associated with said rotatable means for controlling the speed of its rotation; means slidably positioned on said supports adapted for securing the ends of said ropes, means associated with said ropes and confined thereon between said slidable means and said drum for aiding the movement of said ropes, said means associated with the ropes adapted to be positioned on top of said packages, and means associated with said drum for controlling its movement, said means comprising a floating brake disc, a pressure plate positioned in intimate relation to said brake disc, resilient means associated with said pressure plate to maintain said pressure plate in contact with said brake disc, and means associated with said resilient means to vary the pressure of said pressure plate on said brake disc.

7. Apparatus characterized as in claim 6 and, in combination therewith, wherein the means slidably positioned on the supports adapted for securing the ends of said ropes consists of a pair of means, one for each support, each means being channel shaped and having a pair of grooves formed in the underside thereof of a depth and width adequate to permit each of said means to slidably engage the sides of said support, and a pair of eyes extending upwardly from each of said means.

8. Apparatus characterized as in claim 6 and, in combination therewith, wherein the means associated with said ropes and confined thereon between said slidable means and said drum for

aiding their movement consists of a pair of restraining bars, each formed of two sections for partially adapting said bars to follow the top contours of a package, fixed means associated with one section of each of said bars over which said ropes pass, and slidable means associated with each of the other sections of said bars over which said ropes pass, both of said means being adapted to confine said package within the close embrace of said ropes.

9. Apparatus for controlling the opening of compressed packages, comprising supports for said packages, a pair of hollow restraining bars positionable on top of the packages, a pair of anchors slidably secured to said supports, a drum, a pair of ropes secured to said drum and to said anchors, said ropes being threaded through said restraining bars, a pair of grooved pulleys secured to said supports under which said ropes are positioned, means for controlling the movement of said pulleys, means associated with said pulleys for uniformly controlling the movement of said ropes, and means associated with said drum for controlling its movement.

10. Apparatus characterized as in claim 9 wherein the means for controlling the movement of said pulleys consists of a pair of movable brackets, one for each pulley, a stub shaft extending from each of said brackets, a pair of discs, one for each pulley, rotatably positioned on each of said stub shafts, the peripheries of said discs being in direct alignment with its respective pulley, means for maintaining the periphery of said discs in intimate contact with the peripheries of said pulleys, and means for adjustably imparting frictional resistance to the rotation of said discs.

11. Apparatus characterized as in claim 9 wherein the means associated with the drum consists of a shaft for said drum, a bearing for said shaft, said bearing having a collar extending therefrom, a pressure plate slidably positioned on said shaft, a floating brake disc positioned about said shaft and between said pressure plate and one end of said drum, means for continuously forcing said pressure plate against said brake disc, a brake release collar positioned on the bearing and not slidable in relation to the collar of said bearing, a swash plate rotatably positioned on said bearing and adapted to force said brake release collar to slide on the bearing, means associated with the brake release collar and the continuously forcing means for increasing or diminishing the compression on the first mentioned means, and means for adjusting the normal compression of said first mentioned means.
